UNITED STATES PATENT OFFICE

130,257

DESIGN FOR A PIN

Lily N. Sevastopoulos, New York, N. Y.

Application August 30, 1941, Serial No. 103,121

Term of patent 3½ years

To all whom it may concern:

Be it known that I, Lily N. Sevastopoulos, a citizen of the United States, residing in New York, State of New York, have invented a new, original, and ornamental Design for a Pin, of which the following is a specification, reference being had to the accompanying drawing, forming a part thereof.

I claim:

The ornamental design for a pin, as shown.

LILY N. SEVASTOPULOS.
